UNITED STATES PATENT OFFICE.

LICHFIELD WATTON SUTCLIFFE, OF BIRMINGHAM, COUNTY OF WARWICK,
ASSIGNOR OF ONE-HALF TO WILLIAM EDMUND PARKES, OF SOHO HILL,
HANDSWORTH, COUNTY OF STAFFORD, ENGLAND.

SELF-FEEDING AND SMOKE-CONSUMING FURNACE.

SPECIFICATION forming part of Letters Patent No. 274,990, dated April 3, 1883.

Application filed September 6, 1882. (No model.) Patented in England January 20, 1881, No. 254.

To all whom it may concern:

Be it known that I, LICHFIELD WATTON SUTCLIFFE, a subject of the Queen of Great Britain, and resident at Birmingham, in the county of Warwick, England, have invented certain new and useful Improvements in Self-Feeding and Smoke-Consuming Furnaces, applicable in part to domestic fire-grates, (for which I have received Letters Patent in Great Britain, No. 254, dated January 20, 1881,) of which the following is a specification.

The invention consists, first, in the combination, in a furnace, with the fire-chamber and inclined fire-bars, of a fuel-hopper having a cover and a separate fuel-chamber communicating with said hopper through a contracted opening, the said parts being arranged so that the fuel introduced into said hopper feeds itself by gravity through the contracted opening into the fuel-chamber and onto and down the inclined fire-bars. This part of the invention also comprises the combination of a hopper, a fuel-chamber below said hopper, a jointed flap for regulating the flow of fuel into said chamber, inclined fire-bars leading to the mouth of said hopper, a vibratory dead-plate at the upper end of said fire-bars, and a device for operating it.

The invention secondly consists in mechanism for supporting and adjusting the position of the inclined fire-bars; and, thirdly, in the construction and combination of parts of hot-air flues or passages for supplying heated air to the gaseous products of combustion passing from the furnace for burning the said products, also cold-air flues or passages for supplying cold air, when required, to the furnace.

Figure 1 represents a front elevation of a furnace containing my improvements applied to the heating of an egg-ended steam-boiler, and Fig. 2 is a portion of the same with the inclined fire-bars in their lowered position. Fig. 3 is a longitudinal vertical section of Fig. 1; and Fig. 4 is a longitudinal vertical section of a portion of the same with the fire-bars in their lowered position, as in Fig. 2. Fig. 5 is a horizontal section of the furnace, showing the hot and cold air flues, the sections on opposite sides of the fire-bars being taken at dif-

ferent levels. Fig. 6 represents a front elevation of a double furnace constructed according to my invention, each arrangement being independent of the other.

The same letters of reference indicate the same parts in Figs. 1, 2, 3, 4, 5, and 6.

a is the furnace, and *a'* is the gas-generating or coal-distillatory part of the furnace, and *b* the inclined fire-bars of the same, between which fire-bars and the arch *c* the burning fuel is situated. The said fire-bars *b* are capable of being depressed into the position represented in Figs. 2 and 4, or into an intermediate position.

d is the dead-plate of the furnace, capable of a rocking or vibratory motion by means of the lever *d'*, (see the dotted position in Fig. 4,) for the purpose hereinafter explained.

e is a sliding stoking-door, through which the fuel may be fed to the furnace for the first charge. The said door also serves for gaining access to the furnace for any required purpose. The said door may either be lifted by the lever *e'*, (represented in Fig. 1,) or the door may be provided with counterbalance-weights, as represented in the double-furnace, Fig. 6.

Above the gas-generating part *a'* of the furnace is the fuel-hopper *f*, having at its bottom a hinged flap, *g*, by opening which more or less by means of the lever *h*, connected to the said flap by a link, a greater or less quantity of the fuel may be permitted to pass by its own weight from the said hopper into the gas-generating part *a'* of the furnace and onto the dead-plate *d* in a distilled or heated state, from whence it gradually passes down the inclined fire-bars *b*, on which it is consumed, the gases of combustion being effectually consumed and smoke prevented by mixing highly-heated air with the said gases, as hereinafter explained. The hopper *f* is provided at front with a hinged door, *i*, for charging it with fuel; or a sliding door, *k*, as represented in the double furnace, Fig. 6, may be employed for opening and closing the hopper. The inclined movable fire-bars *b* are supported and raised and lowered by the following combination of parts.

In front of the furnace are standards or uprights *l*, to which the fire-bars *b* are hinged at

b^2 , the said fire-bars being carried by a rectangular frame, m . The said frame m , carrying the fire-bars b , is supported by the cams $n\ n$, turning on the centers $n^2\ n^2$, connected by the chains $n^3\ n^3$ to the wheels or pulleys $n^4\ n^4$ on the axis n^5 . By means of the lever n^6 on the axis n^5 , the chains $n^3\ n^3$ may be coiled upon or uncoiled from the wheels $n^4\ n^4$ and the cams $n\ n$ raised or permitted to fall. The said cams are thereby made to raise or lower the inclined fire-bars b . A pawl, n^8 , (see Figs. 3 and 4,) engaging with the ratchet-wheel n^7 on the axis n^5 , preserves the fire-bars in the positions to which they have been adjusted. When the fire-bars b are in the raised position, Figs. 1 and 3, the furnace is ready for working. When it is wished to diminish the heat of the furnace or to entirely stop the working of the furnace, the set of fire-bars b is lowered into the desired position and the flap g of the hopper is closed, so as to cut off the supply of fuel to the furnace. In this way the heat of the furnace may be regulated and the combustion arrested, as hereinafter explained. The motion of the bars b disturbs and breaks up any clinkers which may form upon them. The front of the ash-pit of the furnace is closed by a plate or door, q , and air for the support of the combustion of the fuel in the furnace a passes through valves at p (see Fig. 6) in the said door. By opening the valves at p more or less, the requisite quantity of air may be admitted to the furnace, or the supply of air may be entirely cut off. Should the fuel in the hopper f or in the gas-generating part a' of the furnace clog, it may be agitated or disturbed, so as to cause it to readily pass by its weight into the furnace a , by means of the vibratory dead-plate d , moved by the lever d^2 .

I will now describe the arrangement of flues for heating the air to be supplied to the furnace for mixing with the combustible gases after they pass the arch c .

Under the furnace-bed, and situated in the brick-work, are two sets of horizontal flues, $r\ r$ and $s\ s$, at different levels, each set being divided into two passages by a vertical division. The shape of the flues or passages is best seen in Figs. 3, 4, and 5. The cold air to be heated enters the lower flues, $r\ r$, by the passage r^2 , and after traversing the said lower flues, $r\ r$, it rises at the end r^3 into the upper set of flues, $s\ s$, after traversing which the heated air passes into the flue x , closed at its outer end, (indicated in dotted lines in Fig. 5,) and rising in the vertical flue t enters the cold-air flue u and passes at a high temperature by the side openings, $v\ v$, into the furnace, to mix with and burn the combustible gases passing from the furnace a . The same arrangement of flues is sit-

uated at each side of the fire-bars. Cold air may be admitted to the flue u by opening the door u^2 , the said cold air entering the furnace by the side openings, $v\ v$.

The improvements hereinbefore described, 65 and illustrated in Figs. 1, 2, 3, 4, 5, and 6, may be applied to furnaces for various purposes.

Having now fully described my said invention and the manner of carrying the same into effect, what I claim is—

1. The combination, with the fire-chamber and inclined fire-bars, of the fuel-hopper having a cover, and the separate fuel-chamber communicating with said hopper through a contracted opening, the said parts being arranged as described, so that the fuel introduced into said hopper feeds itself by gravity through the contracted opening into the fuel-chamber and on to and down the fire-bars, substantially as set forth. 75

2. In combination with the fire-chamber and the inclined fire-bars, hinged to the rear ends, mechanism, substantially as described, for raising and lowering the front ends of said bars as one body, and a retaining device for securing said mechanism with the bars in their raised position, as set forth. 85

3. The combination of the hopper, fuel-chamber below said hopper, jointed flap, inclined fire-bars leading to the mouth of said hopper, vibratory dead-plate, and its operating device, substantially as described. 90

4. The combination, with the fuel-chamber and the inclined fire-bars leading to the mouth of said chamber, of the cams and connected mechanism, as explained, for adjusting said bars to different positions, and for retaining them in the position to which they may be adjusted, substantially as described. 95

5. The combination, with the fire-chamber 100 of a furnace and the heated fuel chamber communicating therewith, of the hot-air flues constructed under the furnace, as explained, said flues being at different levels, and each divided by a vertical division, and communicating with 105 said fire-chamber through a vertical flue and side passages, substantially as described.

6. In a furnace, the combination, with the heated fuel or gas-generating chamber and the fire-chamber, of the hot-air flues constructed 110 below the fire-chamber in the bed of the furnace, as explained, and the flue or passage u , through which said hot-air flues communicate with the fire-chamber, said flue or passage u having a door whereby cold air may be admitted, substantially as described. 115
